CLAIM

The ornamental design for a folding handheld stabilizer, as shown and described.

DESCRIPTION

FIG. 1 is a front side perspective view of a folding handheld stabilizer showing my new design, wherein the folding handheld stabilizer is in a first folded configuration;

FIG. 2 is rear side perspective view of FIG. 1;

FIG. 3 is a front side elevation view of FIG. 1;

FIG. 4 is a rear side elevation view of FIG. 1;

FIG. 5 is a left side elevation view of FIG. 1;

FIG. 6 is a right side elevation view of FIG. 1;

FIG. 7 is a top plan view of FIG. 1;

FIG. 8 is a bottom plan view of FIG. 1;

FIG. 9 is a front side perspective view of the folding handheld stabilizer of FIG. 1, wherein the folding handheld stabilizer is in a different, second folded configuration.

FIG. 10 is rear side perspective view of FIG. 9;

FIG. 11 is a front side elevation view of FIG. 9;

FIG. 12 is a rear side elevation view of FIG. 9;

FIG. 13 is a left side elevation view of FIG. 9;

FIG. 14 is a right side elevation view of FIG. 9;

FIG. 15 is a top plan view of FIG. 9; and,

FIG. 16 is a bottom plan view of FIG. 9.
